UNITED STATES PATENT OFFICE

MALCOLM J. FORD, OF BALTIMORE, MARYLAND, ASSIGNOR TO ALMA MANUFACTURING COMPANY, OF BALTIMORE, MARYLAND, A CORPORATION OF MARYLAND.

FASTENER

Application filed November 4, 1931. Serial No. 572,953.

Snap fasteners or ball and socket fasteners, as they are sometimes termed, consist of a socket or female member secured to one side or end or edge of the article to be fastened and a ball or male member secured to the other edge or end of the member or members to be connected, closed or fastened.

The socket or female member of the snap fastener or ball and socket fastener consists of a top which is located on the top or outside of the material or supporting structure to which the fastener is being secured and a tubular socket member which has a flange adapted to engage the other side of the material, the tubular member of the socket being forced into the top and having its edge rolled or turned over outwardly and downwardly, clinching it to complete the fastening whereby the tubular member and the top are held together and secured to the material or supporting structure in their assembled relation.

In the construction of the device in this invention, a snap fastening socket installation is obtained in two parts, the top member and the tubular socket member, each consisting of a single piece and are combined in attaching the snap fastening socket to the material or supporting structure.

An advantage of the improved construction is that it is more nearly foolproof in that with the old type of fastener when the top and socket member or flanged tubular member are combined to complete the female member or socket and attach it to the cloth, the tubular member frequently assumes a cant, i. e., it goes awry, making the attachment of the fastener to the cloth defective and more or less ineffective, and destroying the appearance of the product with which the fastener is being assembled. With the improved form, on the other hand, it is impossible for the flanged tubular member or socket member to get out of alignment as the parts constructed in accordance with the improvement include a guide or centering feature whereby the top and the tubular member are caused to assume the proper alignment in every instance when combined and attached to the cloth so that proper centering and attachment is practically unfailing, and the

parts always center themselves and attach with the proper alignment. It is also of importance that the top or cap and the tubular socket member combine to produce a shearing action on the cloth cutting out a sufficient area as the parts are assembled to provide for the attachment and operation of the socket without punching.

It is further of interest that the inturned portion of the top member is slotted radially and hence fluted about the edges of the apertures which not only assists in the clinching of the members in combining them, but by means of the serrated surface which it presents to the material, it adds to the security with which the fastener is attached to the material and contributes to the ease and convenience of assembling.

In the accompanying drawing I have illustrated a snap fastening socket embodying the features of the invention in the preferred form.

In the drawing:

Figure 1 is a vertical central section on the axis of the fastener assembled and attached to the material to be fastened.

Figure 2 is a bottom plan of the top or shell prior to attachment and assembling with the tubular flanged member or socket member.

Figure 3 is a vertical section through the axis of a tubular socket member prior to assembling.

Figure 4 is a bottom plan of the same.

Referring to the drawing by numerals, each of which is used to indicate the same or similar parts in the different figures, the illustration relates particularly to the female member of the ball and socket or snap fastener, the other half of the fastener being of any preferred form in accordance with the previous practice. This portion of the fastening consists of a top 1 and a tubular flanged member 2, otherwise known as the tubular socket member in that when combined with the top in the assembled condition of the socket or female member the tubular portion 3 of this member 2, forms the peripheral walls of the socket or opening 4 which contains the ball 5 indicated fragmen-

tarily and in dotted lines. The tubular portion 3 is somewhat expanded at 4' by the assembling or clinching operation as it may be termed, forming the concavity of the socket.

More specifically described, the top member 1 resembles to some extent a shallow hat having a crownlike central portion 6 and a rim 7 which is bent downwardly at the edge and turned inwardly and then upwardly as to the edge portion at 8. This latter is preferably fluted, or slotted, in a radial direction at 9 whereby the surplus material is removed and a serrated or slotted area is formed which assists in the clinching action when the parts are combined in attaching them to the material or other supporting structure and contributes to the security of this attachment by virtue of the numerous edges thus presented to the material, permitting it to expand between the edges 10 and into the slots 9.

An important feature of the invention resides in the location and arrangement of the peripheral depending rib 11 whereby the crown or central protuberance is separated from the rim 7. This rim 7 as seen from below, Figures 1 and 2, presents on its outside an upwardly and outwardly inclined peripheral surface 12 which is hereinafter described as having a deflecting and a downwardly rolling action upon the top edge 14 of the tubular flanged member 2 when the top member 1 and the bottom or tubular flanged member 2 also referred to as the tubular socket member are forced together in their assembled relation to grip the material the downwardly deflected edge 14 contacting the inwardly turned edge portion 8 of the top member to assist in the gripping of the material between the inwardly turned edge portion 8 and the flanged bottom 16 of the tubular socket member.

This annular rib 11 is concentric with and spaced slightly inwardly from the circular aperture 15 formed by the turned over edge 15' of the rim or flange 7.

The tubular member 2, as already pointed out, consists of a flange 16 and the upright tubular portion 3 of the member 2. This tubular portion 3 is of a diameter slightly greater than the diameter of the circle formed by the annular rib 11 and slightly less than the diameter of the circle formed by the edge 15' of the turned over portion 8 of the rim 7, in combination with which opening 15 the tubular member 3 may be said to have a sliding fit or a relation approaching the same so that when the tubular portion 3 enters the opening 15, it necessarily is centered with the rib 11 and encircles the same. Under these circumstances, the edge 14 comes in contact with the inclined surface 12 whereby the upper portion of the tubular member 3 is deflected outwardly and

downwardly rolled over inside the annular chamber 18 formed by the turned over rim 7 with its bottom turned portion 8, and the top and socket members are joined together. In this way the tubular portion 3 is slightly expanded at 4'.

The top and bottom members 1 and 2 of the female member of the fastening are thus combined and arranged with the flange 16 and the turned over portion 8 of the rim 7 on opposite sides of the material 22 to which the fastener is to be engaged, the same being preferably apertured at 23 for this purpose so that the edge portions 24 of the material surrounding the aperture 23 are between the flange 16 and the turned over portion 8 which contains the slots 9. As the riveting or clinching action is completed, this material is tightly gripped between these portions 16 and 8, and the socket or female member of the fastener is securely engaged to the cloth or other material to be fastened.

The advantage of this two piece socket assembly is that the cost of production compared with socket assemblies of equal strength and durability is greatly reduced. The ease and reliability of the socket members to properly align themselves upon being assembled upon the material will reduce the possibilities of spoiling the material to which the socket is being attached due to improper assembling, this will also mean a saving on the socket members themselves. This assembling feature is of primary importance, the tubular flanged socket member or portion 2 is guided in its relation to the top 1 by the aperture 15 with which it may have a sliding fit, the rib 11 being spaced inwardly so that under any and all circumstances the edge 14 of the tubular member 3 comes in contact with the outer peripheral surface 12 of the rib whereby the edge 14 is uniformly curled and clinched and the canting of the members relatively to each other with the resulting failure to properly engage and consequent inaccurate seating of the socket is avoided, the fastener being, in fact, foolproof in that it does not require the services of skilled employees to assemble it and attach it to the work in accordance with the practice. It is also of importance that the socket member combines with the one piece top in such a way as to accomplish a most effective shearing action whereby an area of cloth corresponding to the diameter of the socket is cut out by the attachment and assembling of the top and socket member and without any preliminary punching action. This is due to the relation of the guide flange 8 and the opening therein and the location of the annular rib 11 and also to a condition which is essential to the one just stated, i. e., the relation of the diameter of the socket member 2 to the annular rib 11, the edge 14 of the socket member 11 being

just sufficiently larger in diameter than the annular rib 11 to cause the two to cooperate to have a shearing action on the cloth as the two parts are assembled. This result is also dependent upon the fact that the 5 flange 8 is substantially parallel to the portion 7 of the top 1, and immediately overlies the same so that the cutting edges 11 and 14 are immediately adjacent the plane of the cloth and can operate on it without any 10 considerable deflection of the cloth into the top or cap member 1.

I have thus described specifically and in detail a snap fastening socket embodying the features of my invention in the preferred 15 form in order that the manner of constructing, applying, operating and using the invention may be fully understood, however, the specific terms herein are used descriptively rather than in a limiting sense, the 20 scope of the invention being defined in the claims.

What I claim and desire to secure by Letters Patent is:

1. A snap fastening socket installation 25 comprising a top member, a tubular socket member and a supporting structure, said top member being positioned at one side of said supporting structure and having an annular deflecting rib, the outer edge portion of said top member being turned, first downwardly inwardly and then upwardly toward the under surface of the top member the inturned portion of the top member being substantial- 30 ly parallel with the main portion of the top member, a plurality of slits formed in the inwardly and upwardly turned portion of the top member for the purpose of facilitating the bending of the outer edge of said top 35 member and also to secure the top member more firmly to the supporting structure, said tubular member extending through an opening in said supporting structure and having a flanged bottom portion to engage the sup- 40 porting structure upon the opposite side from the top member, the upper edge of said tubular socket being scalloped and flared outwardly, the tubular socket member being of a diameter to fit closely within the opening 45 defined by the inturned slotted edge, the upper edge portion of the tubular socket member engaging the outer side of the annular deflecting rib to deflect the edge portion of said tubular socket member outwardly and 50 downwardly into contact with the inturned slotted portion of the top member to more securely bind the supporting structure between the flanged bottom of the tubular socket member and the inwardly turned portion 55 of the top member.

2. A snap fastening socket installation 60 comprising a top member, a tubular socket member and a supporting structure, said top member being positioned at one side of said supporting structure and having an annular

deflecting rib, the outer edge portion of said top member being turned, first downwardly, inwardly and then upwardly toward the under surface of the top member, the inturned portion of the top member being substantial- 70 ly parallel with the main portion of the top member, a plurality of slits formed in the inwardly and upwardly turned portion for the purpose of facilitating the bending of the outer edge portion of the top member 75 and also to secure the top member more firmly to the supporting structure, said tubular socket member extending through an opening in said supporting structure and having a flanged bottom portion cooperating with 80 the opposite side of said supporting structure and an outwardly flared upper edge portion, the tubular socket member being of a diameter to fit closely within the opening defined by the inturned slotted edge, the upper edge 85 portion of the tubular socket member engaging the outer side of the annular deflecting rib to deflect the edge portion of said tubular socket member outwardly and downwardly into contact with the inturned slotted portion 90 of the top member to more securely bind the supporting structure between the flanged bottom of the tubular socket member and the inwardly turned portion of the top member.

Signed by me at Baltimore, Maryland, this 95
30th day of October, 1931.

MALCOLM J. FORD.
